UNITED STATES PATENT OFFICE.

ADAM A. LONG, OF ROCHESTER, NEW YORK, ASSIGNOR TO THE TAILORS' ACCESSORIES COMPANY, OF ROCHESTER, NEW YORK, A CORPORATION OF NEW YORK.

CLEANING-MACHINE.

1,252,127.

Specification of Letters Patent.

Patented Jan. 1, 1918.

Application filed January 3, 1910. Serial No. 536,087.

To all whom it may concern:

Be it known that I, ADAM A. LONG, of Rochester, in the county of Monroe and State of New York, have invented certain 5 new and useful Improvements in Cleaning-Machines; and I do hereby declare the following to be a full, clear, and exact description of the same, reference being had to the accompanying drawings, forming a part of 10 this specification, and to the reference-numerals marked thereon.

The present invention relates to cleaning machines and it has for an object to provide a construction having a substantially portable brush or other agitator with suction producing means so located that the operative will not be required to support the same during the cleaning operation. Another object of the invention is to provide a construction in which the driving of the brush or agitator will cease when the latter is moved to a certain position. To these and other ends the invention consists in certain improvements and combinations of parts all 25 as will be hereinafter more fully described, the novel features being pointed out in the claims at the end of the specification.

In the drawings:

Figure 1 is a front view of a machine constructed in accordance with the present improvements;

Fig. 2 is a side view of the same machine;

Fig. 3 is a side view of the brush or agitator and the casing by which it is carried, 35 parts being shown in section;

Fig. 4 is a front view of the same parts;

Fig. 5 is a section on the line *a—a* of Fig. 3;

Fig. 6 is a longitudinal section of the casing by which the brush is carried;

Figs. 7 and 8 are detail views of the counterbalance and slack take-up operating on the brush-suspending and driving cable;

Fig. 9 is a detail view of the support for 45 the brush and its casing;

Fig. 10 is an enlarged detail view of the connection of the dust conductor with the fan casing;

Fig. 11 is a central vertical section taken 50 through Fig. 10;

Fig. 12 is a detail sectional view taken through a portion of Fig. 10, and

Fig. 13 is a vertical section of the dust-collecting receptacle.

The present embodiment of the invention 55 has been designed for cleaning cloth or clothes made from cloth, but it is apparent that it contains features which may be embodied in various types of cleaning machines. The work to be cleaned may be arranged on a support or table 1 and acted upon by an agitator 2 which in this instance is in the form of a rotary brush partially inclosed by a casing 3, the brush being preferably carried by a shaft 4 journaled in the 60 casing walls and extended at one end beyond one of said walls to turn in bearings 5 and 5^a arranged within a tubular member 6. The latter is secured to and held in spaced relation to the casing 3 by brackets 7 that 70 are bolted at 8 to said casing, the axial movement of the shaft 4 in the tubular member being prevented by securing a disk 9 thereto at one end so as to coöperate with the outer face of the bearing 5^a. This disk 75 is preferably engaged by a screw plug 10 introduced into the end of the tubular member 6 and preferably carrying an oil cup 11 which feeds oil to the disk for the lubrication of the bearing 5^a, the bearing 5 being 80 lubricated by a cup 12. The tubular member 6 preferably serves as a handle for the control of the brush or agitator and may be incased by a rubber sleeve 13 and a removable rubber cap 14, both of which facilitate 85 the manipulation of the machine and at the same time prevent oil passing from the end of the tubular member.

The driving of the brush or agitator 2 and the suspension thereof is preferably effected 90 by an endless cable 15 which passes about a pulley 16 rigidly secured to the shaft 4 between the casing 3 and the tubular member 6. The cable 15 has its two strands leading upwardly from the pulley 16 about a 95 pair of pulleys 17 arranged side by side and mounted on frames 18 which are pivoted on parallel axes at 19 to swing laterally with relation to the cable so that the brush may be carried toward either end of the 100 table without shifting the cable from the pulleys. From the pulleys 17 the two strands of the cable pass rearwardly to a pair of pulleys 20 and thence downwardly about a pulley 21. Preferably the pulley 105 21 is supported on an upright frame comprising two rods 22 secured at the rear of the work support 1 and having at their up-

per ends an arm 23 which extends forwardly over the work support and serves as a support for the pulleys 17 and 20.

To the end that the slack will be taken up 5 in the endless cable when the brush is moved to different positions and at the same time counterbalance the brush and the parts carried thereby there is employed a weight 24, or other suitable device, which preferably 10 carries a pair of rollers 25 coöperating with both strands of the cable 15 between the pairs of pulleys 17 and 20. This weight is guided vertically on guide rods 26 depending from the arm 23 and having a stop 15 27 at their lower ends to coöperate with the weight and sustain the latter when the brush is moved upwardly to a certain position. Of course, when the weight reaches this stop all tension will be removed from the 20 cable 15 and driving connection between the pulley 21 and the brush 2 will be broken.

The cable, unless otherwise affected, will not stop immediately but will continue to move under its own momentum and with 25 the end in view of effecting an immediate stoppage, there are employed brakes 28, in this instance in the form of levers pivoted to the weight 24 at 28^a and having friction faces 28^b to coöperate with sides of the pulleys 25 and stop rotation of the latter, thus 30 imposing friction on the cable 15. The levers in this instance depend below the weight 24 so that they may engage the stop 27 to be shifted into coöperation with the 35 pulleys 25 when the weight moves to said stop. Springs 28^c act on the levers to hold them out of contact with the pulleys and against the stops 28^d.

The brush may be supported in its inoperative position upon a device comprising 40 two spring arms 29 clamped to one of the rods 22 and having their forward ends converging at 30 to facilitate their introduction through a loop 31 formed on the casing 3 inclosing the brush. An adjustable 45 stop 29^a may be arranged on the arms to limit the movement of the casing on the arms 29.

While the brush is supported in inoperative 50 position the cable 15, of course, is slack and consequently it is desirable to provide some means to prevent the cable leaving the pulley 16. This is accomplished in this instance by a pair of pulleys 33 coöperating 55 with the outer sides of the two strands of the cable and preferably carried upon a movable or swinging member 34 which is journaled on the tubular portion 6 to turn about an axis coincident with the axis of 60 shaft 4, thus permitting the brush to be carried to either end of the table without imposing any strain on the cable. To prevent the swing member moving too freely, a friction member 35 in the form of a plate 65 guided on headed studs 36 is pressed toward

the swinging member by helical springs 37 surrounding said studs, stops 38 projecting into the path of the swinging member at the limits of the movement of the latter. The swinging member 34 may also carry a pin 70 39 which lies between the two strands of the cable and prevents the latter from leaving the pulleys 33.

For the purpose of removing the dust agitated by the brush 2, the casing 3 surrounding the brush is preferably provided with a passageway 48 having an intake arranged at its bottom and to one side of the brush. The outer wall 48^a of the passageway depends lower than the inner wall 48^b 80 so that the dust may enter freely into the passageway but will be prevented from being carried beneath the casing. In order that all possibility of the latter action will be obviated, the wall 48^a carries a depending flexible strip 48^d which provides a tight joint between the material being cleaned and the casing for any operating position of the machine. It is also desirable to control the size of the intake opening and to this end 90 a piece of pliable sheet material secured to the inner wall 48^b of the passageway and is extended upwardly therein. By moving the end 48^c of the sheet material the opening may be varied in size to meet the condition 95 under which the machine is operating.

To the end of producing suction in the passageway 48, a flexible dust conductor or tubing 47 connects with the casing and leads to a stationarily-supported suction-producing means, such for instance as a fan 40 which may be supported on upright rods 22. The tubing 47 may be supported in any suitable manner as by a coiled spring 100 having one end secured to the tubing and 105 the other end attached to an arm 101 extended from the guides 26.

Connection between the fan casing and the tubing is preferably in the form of a member 41 detachably secured to the casing 110 and having an elbow 47^a loosely turning in one end thereof to permit the brush to be moved to either end of the work support without twisting the tubing. The swinging movement of the elbow is limited by stops 115 47^b lying on opposite sides of the elbow and carried by a split clamp or collar surrounding the reduced end of the member 41. The latter has an enlarged chamber 42 and is preferably secured to the fan casing by headed pins 43 on the casing and curved locking slots 44 on the member, a rotation of the latter effecting a locking or unlocking of the parts and a spring pressed bolt 45 on the member coöperating with the fan casing to 120 hold the member against movement on the fan casing. The enlarged chamber 42 is provided to prevent large materials entering the fan casing and in order to cause said materials to collect in the chamber, a cone- 125 130

shaped screen 46 is preferably secured to the fan casing. This screen is self cleaning as its apex is in line with the direction of the air current leading to the fan, thus causing the air to move all lint or the like to the base of the cone so that the latter is always cleared.

From the fan casing 40 the dust is carried to a pipe 50 which through a union 51 connects with the threaded nipple 52 secured to the top 53 of a dust container 54 which has its side walls perforated to permit the escape of air. The top is provided with an annular groove 55 which is secured to the outer edge of a bag 56 of textile material depending into the container 54 to collect the dirt.

The fan shaft 57 has a pulley thereon connected by an endless cable 58 with the pulley 59^a on the shaft 59 which also carries the pulley 21. On the shaft 59 there is also arranged a pulley 60 to which an endless cable 61 connects, the latter in this instance being driven by a motor 62 arranged on the table 1.

Assuming the motor 62 to be running and that the brush is supported upon the arms 29, the operator having placed the goods to be cleaned upon the table grasps the handle of the brush and removes the latter from the support 29. As soon as the brush is moved to a position to elevate the weight 24 from stop 27, the cable 15 begins to move, thus rotating the brush. Upon the engagement of the cloth by the brush, any dust in the cloth will be carried to the intake of the passage 48 and by the fan drawn through the tube 47 and discharged into the bag 56 which will permit the escape of air but will retain the dust particles. As soon as the

brushing operation has been completed the brush is placed upon the arms 29 thus lowering the weight 24 to the stop 27 and causing the latter to shift the brakes 28 into engagement with the pulleys 25 which will effect the stoppage of the cable 15. When the bag 56 is filled with dust the coupling union 51 is manipulated to disconnect the top 53 from the pipe 50 so that the bag 56 may be removed from the chamber 54.

I claim as my invention:

1. The combination with a supporting frame, of a pair of pulleys mounted on the supporting frame, an endless cable passing over the pulleys, a brush suspended from the pulleys by said cable and driven by the latter, suction-producing means fixedly mounted on the frame, a flexible conductor connecting the brush with said suction-producing means, and a yielding support for the flexible conductor.

2. In a cleaning machine, the combination with a supporting frame embodying a table upon which garments may be spread, of a fan fixedly mounted on said frame, a brush, a casing carried with the brush and having an air intake, flexible suspending means connected to the brush and adapted to permit free movement of the latter in all directions over the surface of the table, a flexible conductor between the intake and fan, the latter being arranged at a central point with reference to the swinging path of the brush, and a counterbalance for the brush and casing.

ADAM A. LONG.
